UNITED STATES PATENT OFFICE

JULIUS S. TENNEY, OF NEW YORK, N. Y.

DESIGN FOR A BUCKLE

Application filed October 10, 1930. Serial No. 37,219. Term of patent 3½ years.

To all whom it may concern:

Be it known that I, JULIUS S. TENNEY, a citizen of the United States, residing in the county, city, and State of New York, have invented a new, original, and ornamental Design for Buckles, of which the following is a specification, reference being had to the accompanying drawing, forming part thereof.

Figure 1 is a plan view of a buckle showing my new design and Figure 2 is an edge view thereof.

The reverse side of the buckle is plain.

I claim:

The ornamental design for a buckle, as shown and described.

JULIUS S. TENNEY.
